ABSTRACT: A combination display and storage tube of the type having gas-filled cells sandwiched between flat insulating sheets. One of the two electrodes for applying the sustaining voltage to the gas-filled cells is provided with apertures so that an electron beam may be used to initiate or extinguish the discharge of selected cells.

ELECTRON BEAM ADDRESSED PLASMA DISPLAY PANEL

FIELD OF THE INVENTION

The present invention relates generally to an information storage and/or display tube of the plasma or gas discharge type, and more particularly, to a storage tube having light-emitting elements which may be turned on and off by means of an electron beam.

BACKGROUND OF THE INVENTION AND

DESCRIPTION OF THE PRIOR ART

In the field dealing with the storage and display of information, it has been suggested that plasma display panels be employed to take advantage of their inherent memory; i.e. bistable mode of operation, long life and high brightness. See for example, proceedings, Fall Joint Computer Conference "The Plasma Display—A Digitally Addressable Display With Inherent memory," by D. L. Bitzer and H. G. Slottow, Nov. 1966, p. 541. Such plasma display panels generally comprise three laminated sheets of flat glass plates. The center glass laminate being provided with an array of small gas-filled apertures, referred to as bistable plasma display cells. A visual gas discharge may be achieved by proper selection of the gas mixture and the application of a voltage signal of an appropriate value to selected cells.

The discharge of each cell can be made independent of all other cells and is bistable in nature. That is, a sustaining AC voltage having a value less than the critical firing voltage may be applied across all cells, and although it is sufficient to sustain half-cycle discharges once initiated, it effects no discharge until it is combined with an actuation voltage to render the total cell voltage greater than the critical firing voltage. Once the half-cycle discharge is initiated, the information signal may be removed, yet the cell will continue to emit light under the influence of the sustaining field. Thus, bistable operation is achieved.

Heretofore, the outer laminates of plasma display panels of the type just described have been provided with a crossed-grid arrangement of electrical conductive strips for the purpose of applying the sustaining and actuation voltages to the cells selected for discharge operation. Application of an actuation voltage pulse to two crossed-grid conductors results in the energization or discharge of the gas-filled cell provided at the intersection of the two conductive strips.

The crossed-grid conductor arrangement for addressing the light-emitting cells of plasma display panels has been employed satisfactorily in certain applications. However, the deposition of conductive strips is a time-consuming and an expensive step in the manufacture of panel displays embodying a large number of cells for high resolution. Furthermore, elaborate switching circuitry capable of handling voltages of several hundred volts, is required to properly select the proper conductive strips required to store or display the information.

SUMMARY OF THE INVENTION

The general purpose of this invention is to provide a storage tube of the plasma display type, which embraces all of the advantages of similar plasma display panels yet does not possess the aforescribed disadvantages. To attain this, the present invention utilizes an electron beam addressing arrangement for energizing and deenergizing selected plasma display cells.

An object of the present invention is the provision of a plasma-display-type direct view storage tube, the manufacture of which is susceptible to relatively simple production techniques.

Another object of the present invention is the provision of a direct view storage tube, wherein information can be selectively stored or erased at electron beam scanning speeds.

In the present invention these purposes (as well as others apparent herein) are achieved generally by a storage tube hav-

ing substantially flat insulating members separated by a plurality of plasma discharge cells. The cells are filled with an ionizable gas or gas mixture and electrodes are secured to the outer surfaces of the insulating members. One of the electrodes is continuous and transparent, while the other is a thin conductive metal layer having apertures arranged over gas-filled cells. An AC power supply is connected between the two electrodes to provide a sustaining potential. An electron beam addressing system is employed to direct an electron beam through the apertures of the metal electrode to energize and deenergize selected cells.

BRIEF DESCRIPTION OF THE DRAWINGS

15 Utilization of the present invention will become apparent to those skilled in the art from the disclosures made in the following description, as illustrated in the accompanying drawings; in which

20 FIG. 1 is a perspective view of a storage tube constructed in accordance with the present invention;

FIG. 2 is an enlarged broken-away, cross-sectional view of a display panel portion of the storage tube of FIG. 1;

25 FIG. 3 is an enlarged, detailed view revealing a portion of one of the electrodes deposited on the display panel portion of FIG. 2;

FIG. 4 is a schematic view of the electron beam addressing system and circuit connections of the storage tube of FIG. 1;

30 FIG. 5 is a schematic representation of wall charge accumulation during a portion of the operation of the storage tube of FIG. 1; and

35 FIG. 6 is a graphical representation of waveforms corresponding to the wall charges and applied voltages when the cell is in the "on" state, employed to store and display information by means of the storage tube of FIG. 1.

DESCRIPTION OF THE PREFERRED EMBODIMENT OF THE INVENTION

Referring now to the drawing, wherein like reference

40 characters designate like or corresponding parts throughout the several views, there is shown in FIG. 1 a storage tube, designated 10. The storage tube 10 consists generally of a gas discharge or plasma display panel 12 having a viewing surface

45 14, an evacuated glass envelope 16 sealed to and extending from the panel 12, and an electron beam addressing system 18. The evacuated glass envelope 16 is sealed to the plasma display panel 12 and encloses the electron panel addressing system 18. It may be constructed in accordance with well-known cathode ray tube fabrication techniques.

50 Referring to FIG. 2, it may be seen that the plasma display panel of the present invention consists of three flat sheets of insulating material, such as glass. A center sheet 20 is sandwiched between two outer laminates 22 and 24, and has a plurality of apertures or cells 26 formed through it, by drilling, etching or other means. The density of the cells 26 determines, in part, the resolution of the panel 12. In my experiments, I have used glass sheets 0.006 inch in thickness with a distance between adjacent cells of 0.025 inch, thereby providing a cell density of approximately 1,600 cells per square inch.

55 60 The cells 26 are charged with a suitable gas or gas mixture; for example, a mixture of 95 percent neon and 5 percent nitrogen at a pressure of 300 Torr has been found to provide an extremely fast, bright discharge.

65 The outer surface of the glass sheet 22 is covered by a continuous, transparent electrode 28 such as stannous oxide, SnO_2 , while the outer surface of the outer laminant 24 is provided with a conductive-metal electrode 30, such as an aluminum film layer. The electrode 30 is provided with apertures 32 or openings 32 arranged in registration with the gas-filled cells 26, as may best be seen in FIG. 3.

70 75 Referring now to FIG. 4, the electron beam addressing system 18 of the present invention is shown in schematic form, the evacuated envelope, mounting elements, and external terminals being omitted for purposes of clarity. The electron gun

structure 34 consists of a suitably grounded cathode electrode 36, heated by a filament 38. An accelerating potential represented by a battery 40 is connected between the cathode 36 of the electron gun and the electrode 30 of the gas discharge panel 12. Alternatively, the apertured electrode, 30, may be operated at ground potential with the cathode at a high negative potential. By way of example, the electron gun structure 34 may be an electron gun commercially available from Superior Electronics Company and referred to as a 5AQP electron gun, and the accelerating potential may be 6.5 kv.

It should be apparent that electrons emitted from the cathode 36 of the electron gun structure 34 are caused to be accelerated by the accelerating potential 40 along a path toward the apertured electrode 30 of the panel display 12. Between the panel display 12 and the electron gun assembly 34, there are provided horizontal and vertical deflection plates 42 and 44, between which the electron beam passes and to which appropriate deflection circuitry (not shown) may be externally connected for the purpose of directing the electron beam to selected apertures 32. A beam-gating grid 46 is disposed between the horizontal deflection plates 42 and the electron gun assembly 34 and is connected to beam-gating input terminal, as indicated at 48. The beam-gating input terminals 48 may be connected to an appropriate input signal source synchronized with the external deflection circuitry in accordance with well-known techniques. Thus, it is possible to modulate the intensity of the electron beam emanating from the electron gun assembly 34 during the scanning or sweeping of the beam across the display panel 12.

As may be seen in FIG. 4, an AC voltage source 50 is connected between the electrodes 28 and 30 of the gas discharge panel 12. The AC signal source 50 may be chosen to provide to the electrodes 28 and 30 a 500 volt peak sustaining voltage at a frequency of 300 kHz.

In operation, the AC voltage source 50 is applied to the electrodes 28 and 30 of the plasma display panel 12 to provide the necessary sustaining potential. In the absence of any additional potential across the cells, the sustaining voltage is insufficient to develop the critical firing voltage V_f required to initiate plasma discharge of the gas within the cells 26.

Information can be "written" on or stored within the storage tube 10 by applying an input signal to the beam-gating input terminal 48 so that the beam-gating grid 46 allows electrons to be accelerated from the electron gun cathode 36. These electrons are then deflected by the horizontal and vertical deflection plates 42 and 44; the amount of horizontal and vertical deflection corresponding to deflection potentials applied thereto. The deflection signals may be synchronized with the application of the input signal in any well-known fashion so that selected cells are properly energized.

The deflection plates direct the accelerated electrons to the selected aperture of the aluminum electrode 30, where they accumulate on the surface of the glass sheet laminate 24. This electron accumulation results in an electrical charge, and therefore electrical field, across the gas-filled cells arranged in registration with the aperture to which the electrons have been directed. The electrical field so established will aid the field resulting from the sustaining voltage during one-half cycle. Although the initial potential across the gas-filled cells is insufficient to produce plasma discharge, the additional potential provided by the accumulation of electrons at the aperture surface of glass sheet 24 will trigger the selected cell to its "on" state. Subsequently, the electron beam may be turned off by the beam-gating grid 46 of the electron beam structure 34, yet the energized cell will remain in its "on" state. For the cell to be later extinguished, on command, requires that the charge deposited on the dielectric surface by the electron beam be dissipated after having triggered the cell into the "on" state. I have observed that in the range of vacuum normally used for high-vacuum tubes (10^{-5} — 10^{-7} torr) that the charge dissipates in approximately 10 seconds. This is due to positive ion bombardment from the residual gas in the

vacuum and surface leakage. By proper surface treatment, such as application of a thin, high resistivity, layer of stannous oxide to the surface; the decay of electron beam deposited charge can be made as rapid as desired.

5 The electron beam can then be repositioned by means of the horizontal and vertical deflection plates 42 and 44 to energize another gas-filled cell in a like manner. The sustaining voltage provided by the AC voltage source 50 serves to maintain the plasma discharge of those cells which are triggered on by means of the electron beam, even after the electron beam has been turned off or removed.

10 Thus, it may be seen that information, such as alphanumeric characters, may be written on the plasma display panel 12, where it may be stored indefinitely. The plasma discharge provides a bright visual display of the information. When it becomes desirable to erase an entire character or all of the information displayed by the storage tube 10, the AC voltage source 50 may be turned off, thereby reducing the potential across the actuated cells to a level insufficient to maintain the plasma discharge.

15 The storage characteristic of a plasma display panel arises from the "wall charge" generated in each cell 26 as free charges during the gas discharge. These wall charges tend to migrate to the cell walls under the influence of the sustaining 20 AC potential, and therefore arrange themselves so as to aid or add to the applied AC field at the beginning of each half-cycle of the applied AC sustaining voltage. These wall charges are represented in FIG. 5 for a single gas-filled, energized cell. 25 Waveform representation of the applied AC sustaining voltage is shown in FIG. 6a, while a similar representation of the wall charge potential is shown in FIG. 6b.

20 Referring specifically to the time interval indicated between the time t_0 and time t_1 in FIG. 6, it may be seen at time t_1 the combined electrical field resulting from the wall charge and that of the AC sustaining voltage signal is sufficient to fire or discharge the cell. As may be seen, the discharge of the cell reverses its wall charge polarity very rapidly so that the next half-cycle of operation repeats the discharge phenomenon.

25 However, I have found that during the time interval between time t_0 and t_1 , the electron beam may be pulsed to erase or deenergize a cell which is in its "on" state. The pulsed electron beam deposits a charge on the dielectric surface upon which it impinges after passing through a selected aperture of 30 the aluminum electrode 30. The deposited charge opposes the electric field of the wall charge during the time period between time t_0 and time t_1 . Therefore, if the deposited charge is sufficiently large and if it is applied between time t_0 and t_1 , the total electrical field across the cell will be insufficient to 35 sustain the discharge which would otherwise occur at time t_1 , resulting in the cell reverting to its "off" condition during the next half-cycle of the AC sustaining voltage signal. If the decay of the charge deposited by the electron beam is not too fast relative to the decay of the wall charge, the cell will 40 remain off for all subsequent half-cycles of operation, or until again energized by the electron beam. Hence, an energized cell may be efficiently extinguished in accordance with my invention.

45 In summary, the storage tube of the present invention employs a unique electron beam addressing system directly applied to the dielectric surface material of a plasma-display-type panel in registration with cells to be triggered on or off. Such a storage tube may be advantageously used as a storage 50 oscilloscope where it is important that there be no loss of resolution of a displayed signal trace with the passage of time. Another application of my storage tube would be that of a data display or storage memory; for example, in computer 55 time-sharing scientific and educational applications. In these latter applications the resolution, indefinite storage time and selective erasure, present advantages not available with other types of data display system.

60 Many modifications and variations of the present invention are possible in view of the above teachings. Therefore, it is to be understood that the invention may be practiced otherwise than as specifically described.

I claim:

1. A storage tube comprising
a plurality of substantially flat insulating members defining
storage cells therebetween,
an ionizable gas within and filling said storage cells,
a pair of electrodes external to and separated from said cells
by said insulating members, one of said electrodes defining
apertures registered with said gas-filled cells,
power supply means connected to said electrodes for
providing a sustaining potential less than that required to
initiate a plasma discharge of said gas-filled cells but suffi-
cient to sustain such discharge once initiated,
electron beam addressing means positioned to direct an
electron beam through selective apertures of said one
electrode and onto the surface of one of said insulating
members,
whereby electrical charges may be applied to said gas-filled
cells to selectively initiate discharge or terminate
discharge of the gas provided therein.
2. The storage tube, as defined in claim 1, wherein
said power supply means is an AC voltage source.
3. A storage tube, as defined in claim 1, wherein
the other of said electrodes is a continuous transparent
material.
4. The storage tube, as defined in claim 1, wherein
said one electrode having apertures therein is a substantially
continuous thin-film conducting layer.
5. The storage tube, as defined in claim 1, wherein
said electron beam addressing means, comprises an electron
gun,
a DC potential source connected between said gun and said
one electrode to accelerate electrons emitted by said gun,
deflection plates positioned between said electron gun and
said one electrode for directing electrons emitted by said
gun to selected apertures provided in said one electrode,
and
an electron beam-gating grid positioned between said
deflection means and said electron gun for gating the
emission of electrons from said gun in response to electri-
cal signals applied to said grid.
6. A combination display and storage tube, comprising an
evacuated envelope housing an electron gun, deflection

- plates, and an electron beam-gating grid,
a face plate including a panellike structure of an insulating
material and having a plurality of gas-filled cavities
formed therein, the gas-filled cavities being charged with
an ionizable gas,
- 5 a pair of electrodes external to and separated from said gas-
filled cells by said insulating material, one of said elec-
trodes defining apertures registered with said gas-filled
cells, the other electrode being a continuous transparent
electrode,
  - 10 an AC power supply means connected between said elec-
trodes for providing a sustaining potential less than that
required to initiate discharge of said gas-filled cells, but
sufficient to sustain such discharge once initiated,
  - 15 means for controlling an electron beam emitted by said
electron gun, whereby said electron beam may be selec-
tively applied to said gas-filled cells through said aper-
tures of said one electrode to initiate and extinguish the
plasma discharge of gas provided therein.
  - 20 7. A method of addressing a storage tube of the type having
a plasma display panel comprising a plurality of gas-filled,
light-emitting cells formed within an insulating material, com-
prising the steps of
applying to said gas-filled cells by means of electrodes exter-
nal thereto an AC voltage signal having a magnitude ins-
ufficient to initiate discharge of the gas therein, but suffi-
cient to sustain the light-emitting discharge once ini-
tiated, and
directing an electron beam onto the surface of said insulat-
ing material in registration with selected gas-filled cells,
said electron beam having an intensity sufficient in combi-
nation with said AC voltage signal to trigger the indi-
vidual display cells to their plasma discharge state.
  - 25 8. The method of returning individual gas-filled cells formed
35 within insulating material of a plasma display storage panel to
their initial nonlight-emitting states, comprising the steps of
directing an electron beam to the surface of said insulating
material in registration with cells to be returned to their
"off" state, and
pulsing an electron beam during an appropriate half-cycle
time interval to deposit a charge on said surface in op-
position to wall charges developed within said cells.
